UNITED STATES PATENT OFFICE.

WILLIAM V. LA BAU, OF POUGHKEEPSIE, NEW YORK.

RAILWAY-TIE.

997,452.

Specification of Letters Patent. Patented July 11, 1911.

Application filed April 25, 1911. Serial No. 623,151.

To all whom it may concern:

Be it known that I, WILLIAM V. LA BAU, a citizen of the United States, and residing at Poughkeepsie, in the county of Dutchess 5 and State of New York, have invented certain new and useful Improvements in Railway-Ties, of which the following is a specification, such as will enable those skilled in the art to which it appertains to make and 10 use the same.

This invention relates to railway ties and particularly to ties of this class composed of or formed of concrete, and the object thereof is to provide a railway tie composed of separate 15 blocks or voussoirs, made in the manner of the voussoirs of an arch, whereby the concrete is placed in compression.

It is a well known fact that concrete has very little resistance in tension and that the 20 greatest strength or value is secured by placing said concrete under compression, and my invention consists in forming a railway tie of separate blocks or voussoirs, the contact surfaces of the central voussoirs being in planes 25 which converge to a predetermined point above the tie, while the contact surfaces of the voussoirs adjacent to the central voussoirs are in planes which converge to a predetermined point below the tie, said last 30 named voussoirs serving as supports for the rails and said tie being also provided with end voussoirs having contact surfaces which correspond with the contact surfaces of the adjacent rail supporting voussoirs, whereby 35 the concrete of the tie is placed in compression and the greatest possible strength secured, the separate blocks or voussoirs being also bound together by longitudinal reinforcing rods which pass therethrough.

40 The invention is fully disclosed in the following specification, of which the accompanying drawing forms a part, in which the separate parts of my improvement are designated by suitable reference characters in 45 each of the views, and in which:—

Figure 1, is a side view of a railway tie made according to my invention and showing the rails mounted thereon, the rails and part of the tie being in section;—Fig. 2, a 50 plan view thereof;—Fig. 3, a section on the line 3—3 of Fig. 2;—Fig. 4, a section on the line 4—4 of Fig. 5;—Fig. 5 a sectional view at right angles to that of Fig. 4, and; Fig. 6, a side and end view of a fibrous retaining 55 plug, two of which are placed in the voussoirs which support the railway rails and

into which are passed screws or spikes for securing the rails into position.

My improved railway tie consists of a plurality of central voussoirs *a*, which are 60 three in number in the construction shown, two rail supporting voussoirs *b* and two end voussoirs *c*.

The abutting face of the end of the central voussoirs *a* are in planes which converge to 65 a predetermined point above the tie, while the abutting faces of the voussoirs *b* are in planes which converge to a predetermined point below the tie, and the inner or abutting faces of the end voussoirs *c* are in the 70 same plane as the outer abutting surfaces or faces of the rail supporting voussoirs *b*.

The rail supporting voussoirs *b* are provided with vertically arranged blocks or plugs *d*, the lower ends of which are square 75 in form, as shown at *d*² in Fig. 6, and the outer ends of which are cylindrical in form, as shown at *d*³ and reinforcing or tie rods *e* are passed longitudinally through the tie or the separate blocks or voussoirs of which it 80 is composed and the end voussoirs *c* are provided with recesses *c*² and the rods *e* are provided with washers and nuts *c*³ countersunk in said recesses, which recesses are afterward filled up with concrete as shown at *c*⁴. 85

The rail supporting voussoirs *b* are provided in the opposite side portions thereof with longitudinally arranged yoke-shaped reinforcing rods *f*, the ends of which extend upwardly and are provided with retaining 90 washers or plates and nuts, as shown at *f*², and these yoke-shaped rods *f* are supported by stirrups or loops *g* through the bottom portions of which the yoke-shaped devices *f* pass and which extend upwardly and outwardly 95 and the ends of the side arms or members of which are also provided with hooks *g*². The voussoirs *b* are also reinforced by metal fabric *h* which extends entirely around and within the body portion 100 thereof in line with the longitudinal axis of the tie, the end portions of said voussoirs being unreinforced. My invention, however, is not limited to the exact means herein shown and described for reinforcing the 105 voussoirs *b* and said voussoirs may be reinforced in any desired manner.

In practice, the vertically arranged blocks or members *d* are placed in the voussoirs *b* in the operation of casting or molding and 110 in connecting the rails *i* with the tie or with the voussoirs *b* thereof, I preferably pro-

vide tie plates *j* which are placed on the voussoirs *b* and which are provided with central depressions to receive the base flanges *i*² of the rail, and in practice I also 5 preferably employ screws *k* which are passed downwardly through the tie plates *j* and into the blocks *d*, as clearly shown in Fig. 3.

By reason of the vertical form of the blocks *d* which are preferably composed of 10 wood, the said blocks cannot be drawn upwardly through the voussoirs *b*, and said blocks or plugs *d* are treated with creosote, paraffin or other suitable preservative material, and said blocks or plugs are also 15 preferably bored at the top to receive the screws or spikes *k*; but my invention is not limited to the use of screws, and ordinary spikes may be driven into the blocks or plugs *d* if desired.

20 With the construction herein shown and described, the angles of the abutting faces of the voussoirs *a* and *b* may be made equal to the angle of friction of concrete or between the said angle and a vertical line, the 25 angles being considered with reference to the base of the tie or side opposite the rails, and the point toward which the abutting faces of said voussoirs converge may be raised or lowered, or the angle of said abutting 30 faces to the longitudinal axis of the tie may be varied, and this is also true of the abutting faces of the voussoirs *b* and *c*.

It may not be necessary, under all conditions 35 to reinforce the voussoirs *b*, but this should be done when said voussoirs are made so long that both tension, compression and shear have to be taken care of.

40 The number of voussoirs may be varied as may also the lengths thereof according to the length of the tie desired, and the ties may also be made of different sizes according to the load to be passed thereover, and my improved railway ties may be used on any kind or class of railways or in the construction 45 thereof.

Having fully described my invention,

what I claim as new and desire to secure by Letters Patent, is;—

1. A concrete railway tie composed of central blocks, rail supporting blocks, and end blocks, the abutting surfaces of the central blocks being in planes which converge to a point above the tie, and the abutting surfaces of the rail supporting blocks being in planes which converge to a point below 55 the tie, and the abutting surfaces of the end blocks corresponding with the adjacent abutting surfaces of the rail supporting blocks.

2. A concrete railway tie composed of central blocks, rail supporting blocks, and end blocks, the abutting surfaces of the central blocks being in planes which converge to a point above the tie, and the abutting surfaces of the rail supporting blocks being in planes which converge to a point below 60 the tie, and the abutting surfaces of the end blocks corresponding with the adjacent abutting surfaces of the rail supporting blocks, said rail supporting blocks being also provided with fibrous plugs. 70

3. A concrete railway tie composed of central blocks, rail supporting blocks, and end blocks, the abutting surfaces of the central blocks being in planes which converge to a point above the tie, and the abutting surfaces of the rail supporting blocks being in planes which converge to a point below 75 the tie, and the abutting surfaces of the end blocks corresponding with the adjacent abutting surfaces of the rail supporting 80 blocks, said rail supporting blocks being also provided with fibrous plugs, and being also independently reinforced.

In testimony that I claim the foregoing as my invention I have signed my name in 85 presence of the subscribing witnesses this 24th day of April 1911.

WILLIAM V. LA BAU.
